UNITED STATES PATENT OFFICE.

ADELMER M. BATES AND ALBERT KRASA, OF CHICAGO, ILLINOIS, ASSIGNEES TO BATES
VALVE BAG COMPANY, OF CHICAGO, ILLINOIS, A CORPORATION OF WEST VIR-
GINIA.

SEWING, SEVERING, AND SEAM-REENFORCING MACHINE.

Application filed February 1, 1923. Serial No. 616,372.

Our invention relates to an improved sewing, severing and seam reenforcing machine. More specifically, it relates to improvements in a machine for sewing a reenforced closing 5 seam across the top of a filled bag, and cutting off the walls of the bag beyond the seam.

The objects of our invention are to provide a new and improved mechanism for simultaneously and automatically feeding re-enforcing strips to a bag closure, stitching a seam through said strips and the bag walls to close the bag and secure the strips in place as reinforcements for the seam, and cutting 15 off the surplus bag material beyond and parallel with the seam. The features of improvement will appear as the description proceeds, and are pointed out in the appended claims.

20 The preferred embodiment of our invention is illustrated in the accompanying drawings, in which:

Figure 1 is a perspective view of the assembled machine; Fig. 2 is an end view of 25 the sewing and severing means, looking from beneath in Fig. 1; Fig. 3 is a section on line 3-3 of Fig. 1; Fig. 4 is a section on line 4-4 of Fig. 2; Fig. 5 is a section on the line 5-5 of Fig. 4, but showing the knife bar 30 lowered; Fig. 6 is a plan view of the throat plate; Fig. 7 is a sectional view of the 35 adjusting clamp for the work support, and Figs. 8 and 9 are a plan view and side elevation, respectively, of a modified form of work support.

The device consists of a pedestal A, upon which are mounted a sewing and severing machine B, a motor C for operating the machine, and a work support D.

40 The sewing machine has a needle 10 with a common form of needle operating means and a thread supply, which need not be described here. The needle works through a presser foot 11 and throat plate 12. The presser foot and throat plate have guides 13 14 for reenforcing strips 15 16, which are fed to opposite sides of the seam which is being sewn. The reenforcing strips are mounted in rolls 45 on supports 17 18, carried by the pedestal A. The throat plate, as shown in Fig. 6, has a needle slot 19, a reinforce feeding slot 20,

feeding slots 21 22, and a cutter slot 23. The throat plate strips 24 25, on each side of the cutter slot, are toothed for a purpose which will be stated later.

55 Beneath the needle and on the end of the operating shaft 26 there is a single looper 27. The feed dogs 28 29, working through slots 21 22 in the throat plate, are carried by a block 30, which is fastened by means of a screw 31 to a carrying plate 32.

The shaft 26 carries an eccentric 33, surrounded by an end of a link 34, which end fits in a horizontal slideway in a block 35. This arrangement transmits vertical movement from eccentric 33 to block 35. The block 35 has a depending lug 36 channeled, as shown at 37, in Fig. 5. The feed-dog carrying plate 32 is clamped against the channeled face of the lug 36, as by means of 65 screws 38 and 39 passing through the face plate and into the ends of a bar 40, on the other side of the lug. In this way the plate may be adjusted on the lug and at the same time forms a side for the channel 37. This 70 channel 37 constitutes a slideway for a bar 41, to the upper end of which a knife 42 is fastened by means of a screw 43. The lower end of the slide bar 41 carries lugs 44 45, forming a channel for receiving operating 75 member 46.

The block 35 has an arm 47 pivotally mounted at 48 on a link 49, pivoted to the frame at 50. This link 49 carries a slotted lug 51, to which is adjustably pivoted the 80 free end of link 34. The slot allows the link 34 to be connected at different distances from pivot 50, so that the actuation of link 34 by eccentric 33 may transmit the desired horizontal movement to arm 47 and block 35.

85 The knife-carrying slide bar 41 is operated by means of an eccentric 52 on the shaft 26 through a link 53, pivoted to one end of an arm 54 on rock shaft 55, there being on the other end of the rock shaft 55 an arm 56, to 90 the end of which is pivoted the operating member 46, previously mentioned.

The work support consists of a frame 60, having a lug 61, by which it is adjustably mounted on the pedestal A in the following 100 manner. In the side of the pedestal there is a vertical slot 62. Plates 63 64 are bolted

to the pedestal and slightly overlap the edges of the slot so as to form a channel in which works a T-shaped head 65 on the lug 61. A screw 66, passing through the lug 61 and the T-shaped head 65, may be tightened against the bottom of the groove 62 and press the arms of the head 65 out against the plates 63 64, thereby clamping the lug and supporting frame in the selected vertical position.

The work-supporting carriage shown in Fig. 1 consists of a platform 70 mounted on wheels 71 running on tracks 72 73 on the frame 60. It is generally advantageous to have one end of the track slightly lower than the other, so that the carriage will be returned by gravity to the position shown in Fig. 1. In the form shown in Figs. 8 and 9, a plurality of shafts 74 bearing work-supporting rollers 75 are substituted for the carriage shown in Fig. 1. By staggering these rollers 75 as shown in the drawings, a substantially continuous rolling support for the work is obtained.

In operation, a filled bag is placed on the work support and the top of the bag is fed into the sewing machine. A reenforcing member is fed to each side of the seam, and the needle sews through the two reenforcing members and the bag fabric to form a bag-closing seam. After the bag has passed through the machine, the reenforcing elements may be severed, if desired, by a cutting device diagrammatically indicated at 80 in Fig. 1, which may be driven from the motor by a belt 81. As the material is fed through the machine, the edges are trimmed or cut off by the knife 42. As will be seen, the cutter-knife has a compound movement. It is caused to move transversely of the direction of travel of the fabric by the movement of slide-bar 41, actuated by eccentric 52, while it also moves with the feed dogs in the line of travel of the fabric. The cutting stroke of the knife is just to begin in the position shown in Figs. 1 to 4, and takes place while the feed dogs are being moved against the direction of travel of the fabric to get a new hold. During this stroke, the knife moves with the feed dogs against the direction of travel of the fabric, and at the same time is drawn through the throat plate, so that the severing edge of the knife has a drawing cut against the fabric, the teeth on throat plate bars 24 25 aiding in holding the fabric firmly during the cutting operation. As shown in Fig. 2, the cutting edge of the knife is provided with tooth notches 82, and on one side has clearance grooves 83 extending from the tooth notches. During the working stroke of the feed dogs the knife advances with them, and at the same time is pushed through the throat plate and through a slot in the presser foot. Teeth 84 are shown on the rear side of the knife,

and they assist in clearing the slot during the working stroke of the feed dogs and the return movement of the knife.

In Fig. 5 the knife is shown in the position it assumes at the end of the working stroke of the feed dogs. It will be noted that at this time the knife fastening screw 43 is in line with an opening 85 in the feed dog carrying plate 32. This opening, 85 provides access to the screw 43, so that the knife may be taken out, to insert a different knife or for any other purpose, without disturbing the rest of the mechanism.

The single looper is especially advantageous when a cutter is carried by a slide bearing in the feed dog support, as shown in this application. It is also of especial importance when it is desired to use a reenforcing strip on one side only of the bag, in which case the reenforcing strip may be best omitted from the chain side of the stitch.

In the combination shown, the character and arrangement of the knife, the reenforce guides, feed dogs, etc., are all especially adapted for use where paper or similar fabric is to be sewed and cut, and the organized machine is especially adapted for closing and trimming the ends of filled paper bags; but it will be obvious that various changes may be made in various features, and that some of the features may retain some of their advantages when used in other combinations, so that I do not wish to limit the construction or combination of the several features except as stated in the appended claims.

What we claim is:

1. In a sewing machine, a feed dog carrier having therein a slideway, a cutter bar mounted in the slideway, and means to reciprocate the bar in the slideway.

2. In a sewing machine having a feed dog, a slide bearing moving with the feed dog, a cutter bar slidably mounted in the bearing, and means to reciprocate the bar in the bearing.

3. In a sewing machine having a feed dog, a slide bearing moving with the feed dog, a cutter bar mounted in the bearing for reciprocation in a direction normal to the movement of sewn fabric, and means to reciprocate the bar in the bearing.

4. In a sewing machine, a feed dog carrier having therein a slideway, a cutter bar mounted in the slideway, an operating shaft, means connected to the shaft for operating the carrier, and other means connected to the shaft for moving the bar in the slideway.

5. In a sewing machine, a feed dog carrier having therein a slideway normal to the direction of travel of the sewn fabric, a cutter bar mounted in the slideway and having a guideway parallel with the direction of travel of the sewn fabric, and an operating member working in the guideway and con-

- trolling the movement of the cutter bar normal to the fabric.
6. In a sewing machine, a feed dog carrier having therein a slideway normal to the direction of travel of the sewn fabric, a cutter bar mounted in the slideway and having a guideway parallel with the direction of travel of the sewn fabric, and means controlling the movement of the cutter bar normal to the fabric, said means comprising a rock shaft having two arms, one of which is connected to an eccentric on the operating shaft and the other of which carries a member working in the transverse guideway in 15 the cutter bar.
7. In a sewing machine, a throat plate having slots therein, a carrier having dogs working through certain of said slots and having a slideway, a cutter bar mounted in 20 the slideway and carrying a knife working through a slot in the throat plate, and means to reciprocate the bar in the slideway.
8. In a sewing machine, a throat plate having slots therein, a carrier having dogs 25 working through certain of said slots and having a slideway, a cutter bar mounted in the slideway and carrying a knife working through a slot in the throat plate, and means for moving the bar to thrust the knife out 30 through the throat plate during the working stroke of the feed dogs and drawing it back during the return stroke of the dogs, the face of the plate being toothed beside the knife slot.
- 35 9. In a sewing machine, a feed dog carrier having therein a slideway, a cutter bar mounted in the slideway and a knife fastened by a screw to the bar, there being an opening in a wall of the slideway to give 40 access to the head of the screw in one position of the bar.
10. In a sewing machine having an intermittent feed, a member having a slot parallel with the direction of travel of the sewn 45 fabric, a knife working through the slot and having a cutting edge normal to the edges of the slot, and means to move the knife with the fabric while the fabric is moving and so as to produce a drawing cut against 50 the edges of the slot while the fabric is at rest, the edges of the slot being notched to hold the fabric from movement away from the knife.
- 55 11. In a sewing machine, a feed dog carrier having therein a slideway, a cutter bar mounted in the slideway, a knife mounted on the bar, an operating shaft, means connected to the shaft for operating the carrier, other means connected to the shaft for moving the 60 bar in the slideway, and a member upon which fabric to be sewed may rest, said member having a slot therein through which the knife works, the edges of the slot being notched to hold the fabric from movement 65 away from the knife.
12. In a sewing machine, a needle, a shaft having on its end a single looper adapted to cooperate with the needle, a feed dog carrier closely adjacent the looper and having therein a slideway, a cutter bar mounted in the 70 slideway, and means to reciprocate the bar in the slideway.
13. In a sewing machine, a needle, a shaft having on its end a single looper adapted to cooperate with the needle, a feed dog carrier closely adjacent the looper and having therein a slideway, a cutter bar mounted in the 75 slideway, and separate means connecting the carrier and the bar to the shaft.
14. In a sewing machine, a feed dog, a 80 slide bearing moving with the feed dog, a cutter bar mounted in the bearing for reciprocation in a direction normal to the movement of the sewn fabric, and means to guide a reenforcing element to each side of 85 the seam as it is being sewed.
15. In a machine for closing and trimming the tops of filled bags, an adjustable support upon which a filled bag may rest and be moved substantially horizontally and a 90 sewing and trimming machine in fixed position above said support and adapted to sew and trim the top of a bag on the support, the sewing machine comprising a feed dog operable to feed the bag along the support 95 and through the machine and having therein a slideway, and a cutter bar mounted in the slideway and carrying a knife adapted to trim the bag as it is fed through the machine. 100
16. In a machine for closing and trimming the tops of filled bags, a pedestal having therein a vertical slot, a plate along each side of the slot and overlapping the slot, a support having a T-shaped head adapted to work in the slot, a screw operable through said head and against the slot to clamp the head in adjusted position, a work carrier on the support upon which a filled bag may rest and be moved substantially horizontally, and a 105 sewing and trimming machine in fixed position on the pedestal and adapted to sew and trim the top of a bag on the support, the sewing machine comprising a feed dog operable to feed the bag along the support 110 and through the machine and having therein a slideway, and a cutter bar mounted in the slideway and carrying a knife adapted to trim the bag as it is fed through the machine. 115
17. In a machine for closing and trimming the tops of filled bags, a pedestal having therein a vertical slot, a plate along each side of the slot, and overlapping the slot, a support having a T-shaped head adapted to work in the slot, a screw operable through said head and against the slot to clamp the head in adjusted position, a work carrier on the support upon which a filled bag may rest and be moved substantially horizontally, 120
- 125
- 130

and a sewing and trimming machine in fixed position on the pedestal and adapted to sew and trim the top of a bag on the support.

18. In a sewing machine, a member having a slot parallel with the direction of travel of the sewn fabric, and a knife working through the slot and having a cutting edge substantially normal to the line of travel of the fabric, the cutting edge being notched and there being, in one face of the knife, a groove forming a continuation of each notch.

19. In a sewing machine, a feed dog, a slide bearing movable with the feed dog, a cutter-bar mounted in the bearing for reciprocation in a direction substantially normal to the line of movement of the sewn fabric, and a knife carried by the bar, the knife having a notched cutting edge running substantially in the direction of its reciprocation, grooves in one face termi-

nating in the respective notches, and clearing teeth on the edge opposite the cutting edge.

20. In a device for sewing and trimming 25 the tops of filled bags, an antifriction support for a filled bag and a sewing head overhanging the support, said head comprising a feed dog and means to actuate said dog to feed the top of a bag through the sewing head and pull the bag along the anti-friction support, there being a slideway in said dog transverse to the direction of feed, 30 a cutter bar mounted in the slideway, and means to reciprocate the bar in the slideway 35 to trim the top of a bag as it is fed through said head.

In testimony whereof we have hereunto subscribed our names to this specification.

ADELMER M. BATES.
ALBERT KRASA.
